[57] ABSTRACT

A method of casting a concrete pile in situ using a former which is extracted following the casting of the pile, the former, with a concrete plug cast in its lower end and while the plug is in a semi-hardened state being driven into the site by the action of a driving monkey on the plug and then the combination of a counterweight (driving monkey) rested on the plug and a vibrator extractor on the former used to free any bond between the plug and former and withdraw the former part-way up the plug whereupon the counterweight is removed and reinforcing and cementitious mixture is placed in the former to form the pile and the former is then extracted using the vibrator at a rate commensurate to the hardening rate of the cementitious mixture.

PILING METHODS

This invention relates to a method of casting concrete piles in situ.

BACKGROUND OF THE INVENTION

The intention of this invention is to provide a cast, in situ, concrete piling method enabling a former for the cast pile to be extracted following the casting operation.

SUMMARY OF THE INVENTION

According to one aspect of this invention there is provided a cast, in situ, concrete piling method comprising the steps of casting a concrete plug in an end of a former and while the plug is in a semi-hardened state driving the former with the plug lowermost into a site by the use of a driving monkey acting on the plug, providing a counterweight on the plug, mounting a vibrator extractor on the former and operating the extractor at a frequency that will free any bond between the former and plug and then withdrawing the former part-way up the plug, removing the counterweight, inserting reinforcing and cementitious mixture into the former to form a pile and using a vibrator extractor to extract the former at a rate commensurate to the hardening rate of the cementitious mixture.

BRIEF DESCRIPTION OF THE DRAWINGS

FIGS. 1, 2 3 are partial side elevations, partly in cross-section indicating the steps of the method; and

FIG. 4 is a view similar to FIGS 1, 2 and 3 indicating an additional step to the method which it may be desirable to include depending on the site involved.

DETAILED DESCRIPTION OF CERTAIN PREFERRED EMBODIMENTS

Referring now more particularly to FIG. 1, a cylindrical steel tube is utilized as a former 1 to cast a pile in situ. A concrete plug 3 is cast in an end of former 1. Preferably plug 3 extends longitudinally of former 1 a distance approximately two and a half times the diameter of former 1. With this arrangement it is found that the adhesive bond inherent in plug 3 while in a semi-hardened state combined with a frictional bond, mentioned in more detail hereinafter, between former 1 and plug 3 will withstand the following described driving operation.

Former 1, with plug 3 lowermost, is then driven into the required site (ground level being indicated by Line 5) to the necessary founding depth. A driving monkey 6 preferably of a diameter equal to at least half the diameter of former 1, is utilized in conventional manner within former 1 to act on plug 3 in this driving operation.

It is found that the frictional bond, mentioned aforesaid created by the action of monkey 6 on plug 3 in its semi-hardened state tends to compressively distort plug 3 creating a radially directed component of the driving action bearing against former 1 resulting in a frictional bond being created therebetween which in combination with the adhesive bond is sufficient to cause former 1 to be dragged down with plug 3.

The actual degree of hardening of plug 3 is not unduly critical however the timing of the commencement of this operation involves a certain degree of acquired skill. The timing is dependant upon the harden-

ing characteristics of the cementitious mixture utilized in plug 3, the type of site involved and the particle size of the constituents of the mixture of plug 3.

Normally this operation can be commenced within a matter of hours of casting plug 3 within former 1. At the other end of the possible range plug 3 may be cast in former 1 and by keeping plug 3 damped commencement of this operation may be delayed, for example, overnight.

On completion of the driving operation a counterweight preferably driving monkey 6 is then rested on plug 3.

Referring to FIGS. 2 and 3, a vibratory extractor 9 is then clamped in conventional manner to the head of former 1. By adjusting the frequency of the vibrator extractor 9 it is found that any remaining adhesive bond between plug 3 and former 1 is freed. The positioning of the counterweight upon plug 3 during the vibrating action appears to nullify the vibrating action upon plug 3 as a whole which remains substantially unaffected in its position in the site, the vibrating action tending to free the peripheral section of plug 3 outside its central portion under the compression influence of monkey 6 resting thereon.

During this step and maybe overlapping with the next step a pre-mixed cementitious grout 7 is preferably placed on top of plug 3. Experiments indicate that grout 7 assists, by lubricating, the freeing of any bond between plug 3 and former 1 and the subsequent withdrawal of former 1, described hereinafter. The cementitious grout 7 has an additional function also mentioned hereinafter.

In the preferred form the vibrator extractor 9 is adjusted to operate at approximately 1,250 oscillations per minute, it being found that at this frequency, maybe in combination with the addition of cementitious grout 7, the freeing of the bond between plug 3 is obtained within a short interval of time.

Following the freeing of any bond the vibratory extractor 9 is used in conventional manner to withdraw former 1 part-way up plug 3, preferably an amount equal to twice the diameter of former 1. Plug 3 remains substantially at its grounding level and the cementitious grout 7 penetrates about the periphery of plug 3 and will enter any annular space 8 which may be formed, particularly in harder ground, by the withdrawn of former 1.

Referring to FIG. 4, further cementitious mixture, preferably tending to be "dry," may at this stage be placed on plug 3 and driving monkey 6 then used to force that cementitious mixture about the periphery of plug 3 to form a bulb base 10, the necessity or otherwise of this step of the operation being basically dependant upon the type of sub-strata of the site.

Driving monkey 6 is then withdrawn and the required reinforcing 11 and cementitious mixture 12, which is preferably of high workability, for a pile is placed within former 1. The vibrator extractor 9 is then used to slowly extract former 1 from the site. A vibratory type extractor is preferably used as its vibrations facilitate compaction of cementitious mixture 12. The timing of this extraction process is related to the hardening rate of cementitious mixture 12 which in the form of the required pile "takes-up" the shaft left by extraction of former 1.

By such method it will be appreciated that the possibility of loose or unstable material adjacent the shaft intruding thereinto is alleviated.

Thus by this invention there is provided a method of casting a pile in situ which enables a former for the pile to be removed and may be utilized in another piling operation.

The terms and expressions which have been employed here are used as terms of description and not of limitation, and there is no intention, in the use of such terms and expressions, of excluding equivalents of the features shown and described, or portions thereof, it being recognized that various modifications are possible within the scope of the invention claimed.

What is claimed is:

1. A method of casting a pile in situ comprising the steps of casting a concrete plug in an end of a former and while the plug is in a semi-hardened state, driving the former with the plug lowermost into a site by the use of a driving monkey acting on the plug, providing a counterweight on the plug, mounting a vibrator extractor on the former, and operating the extractor at a frequency that will free any bond between the former

and plug and then withdrawing the former part-way up the plug, removing the counterweight, inserting reinforcing cementitious mixture into the former to form a pile and using a vibrator extractor to extract the former at a rate commensurate to the hardening rate of the cementitious mixture.

2. A method of casting a pile in situ as claimed in claim 1 further comprising the step of inserting a cementitious grout during the process of operating the extractor to free any bond between the former and the plug.

3. A method of casting a pile in situ as claimed in claim 1 wherein the driving monkey is utilized as the counterweight and wherein the vibrator extractor used in freeing the bond between the plug and former is also used in extracting the former from the site.

4. A method of casting a pile in situ as claimed in claim 1 including the step of applying a cementitious mixture to the top of the plug following the part-way withdrawal of the former from the plug and then using a driving monkey to force the cementitious mixture past the periphery of the plug to form a bulbed base.
